UNITED STATES PATENT OFFICE.

JOHN W. MORGAN, OF MARYSVILLE, CALIFORNIA.

DISK PLOW.

1,226,793.

Specification of Letters Patent.

Patented May 22, 1917.

Application filed April 10, 1916. Serial No. 90,104.

To all whom it may concern:

Be it known that I, JOHN W. MORGAN, a citizen of the United States, residing at Marysville, in the county of Yuba, State of California, have invented certain new and useful Improvements in Disk Plows; and I do declare the following to be a full, clear, and exact description of the same, reference being had to the accompanying drawings, 10 and to the characters of reference marked thereon, which form a part of this application.

This invention relates to improvements in disk plows and particularly with respect to 15 the steering control means of the same together with a means whereby the width of the furrows cut by the plow may be readily altered without the necessity of adding to or taking away from the number of the 20 disks as is now the common practice. I accomplish this by changing the angle at which the plow is steered and then in combination therewith altering the position of the disk so as to adjust every angle to suit 25 the changed condition. The invention embodies certain other control means in order to render the structure efficient for the purposes, all of which will appear by the reading of the following specification.

30 A further object of the invention is to produce a simple and inexpensive device and yet one which will be exceedingly effective for the purposes for which it is designed.

35 These objects I accomplish by means of such structure and relative arrangement of parts as will fully appear by a perusal of the following specification and claims.

In the drawings similar characters of reference indicate corresponding parts in the 40 several views.

Figure 1 is a top plan view of the complete disk plow.

Fig. 2 is a sectional view showing one of 45 the furrow wheels and the means for raising and lowering same.

Fig. 3 is a sectional view showing the land wheel and the means for turning same.

Referring now more particularly to the 50 characters of reference on the drawings, the numeral 1 designates the main frame of the plow, projecting centrally from which as at 2 is a bracket in which is turnable the supporting post 3 of the main wheel 4. At one 55 end of the frame 1 is turnable the support-

ing post 5 of the front furrow wheel 6, and at the other end is turnable the supporting post 7 of the rear furrow wheel 8.

On the post 3 is a steering bell crank 9, on the post 5 is a steering lever 10 and on the post 7 is a steering lever 11. A connecting rod 12 leads from the lever 10 and connects with one end of the bellcrank 9 and is provided with a sliding adjustment consisting of the pin 12^a slidable in the main 60 rod 12 and arranged to be fixed at any desired position therein by means of a set-screw 12^b. Similarly, a connecting rod 13 connects from the lever 11 with the other end of the bellcrank 9 and is provided with 65 an adjustment comprising the pin 13^a slidable within the main rod 13 and arranged to be set at any desired position therein by means of a set-screw 13^b. By means of these 70 adjustments just described the relative positions of the land wheel and the furrow wheels may be fixed at will, both for the purpose of narrowing or widening the furrow to be cut and for the purpose of overcoming any side drag against the plow, and 75 it will be readily apparent that this adjustment can be had to an extreme nicety.

The numeral 14 designates the steering arm suitably connected with the post 5 and being connected at its outer end with the 80 steering bar 15, while the numeral 16 designates the steering strut extending outwardly from the main frame parallel with the member 15.

The numeral 17 designates the draw bar 85 which is secured to the main frame and provided along its length with a plurality of holes 18 whereby the drag chain 19 may be set at different relative positions and properly lined up with the draft of the plow to 90 overcome the side thrust or drag. The said chain 19 is suitably clamped to the members 15 and 16 by clamps 20.

The numeral 21 designates the disk 100 brackets carrying the disks 22, which disk brackets are each primarily pivoted to the main frame 1 by the king bolts 23. The outer end of each bracket is provided with a plurality of holes 24 whereby the brackets 21 are again bolted to the frame by means of bolts 25. To change the angle of the disks, the bolts 23 are loosened and the bolts 25 removed and disposed through different holes 24, which will change the relative angles of the disks at will, and when 110

so changed the bolts 25 and 23 are again tightened to hold the brackets 20 rigid in the desired position.

The furrow wheels 6 and 8 are arranged 5 to be raised and lowered at will, but inasmuch as this raising and lowering structure is not a part of the present invention, I have not given here a specific description of the same since it is apparent that 10 a great many different means might be employed for that purpose.

Describing now the operation of the plow, the drag can be first primarily determined by positioning the chain 19 at any 15 one of the holes 18 on the draw bar 17 and, when the proper drag is thus obtained, a further adjustment can then be had by means of the rods 12 and 13, by further adjustment of which the relative positions 20 of the land and furrow wheels may be determined. Assuming now that the plow was being operated with the parts in the position shown in Fig. 1 and it was desired to narrow the width of the furrow, the 25 relative positions of the land and furrow wheels would be changed by means of the adjustment rods noted so that the plow would tend to pull more to the right. This of course would then move the disks out 30 of proper position relative to the changed position of the plow proper, but this could be quickly and easily remedied by adjusting the brackets 21 in the manners set forth. Vice versa, to make a wider furrow, the 35 relative positions of the means noted would be changed so as to steer more to the left, and, in that event, the brackets 21 would be readjusted to a reverse position to that of the wheels when steering toward the 40 right.

To merely slightly change the draft to the right or the left to avoid side draft and to render it easy to keep the motive power out of the furrow, the position of 45 the chain 19 on the draw bar 17 may be altered at will without the necessity of altering the connections of the chain 19 with the draw bar of the motive tractor or other motive means.

50 Another great advantage to be derived by the use of my three-wheel control is that since all of the steering levers of the wheels are connected with each other, they move in the same relative relation when turned 55 and thus permit of a much easier and shorter turn to be made due to the fact that the amount of drag and side draft in turning is greatly lessened since the wheels all conform to the same curve made by the 60 plow in the turning operation.

As noted, each of the wheels may be adjusted and set independently of the other or all of them may be adjusted as a unit, and it is to be readily understood that this will make possible a very minute adjustment so as to practically do away with any unnecessary side draft or drag either in the straight pull or in turning. 65

From the foregoing description it will be readily seen that I have produced such 70 a device as substantially fulfills the object of the invention as set forth herein.

While this specification sets forth in detail the present and preferred construction of the device, still in practice such deviations from such detail may be resorted to as do not form a departure from the spirit 75 of the invention, as defined by the appended claims.

Having thus described my invention what 80 I claim as new and useful and desire to secure by Letters Patent is:

1. A plow comprising a supporting frame, plowing devices carried by the frame, a draw bar on the frame, a steering strut 85 fixed to the front of the frame at right angles to the direction of the movement of the plow, a flexible draft member connected with the draw bar and to the steering strut, furrow wheels and a land wheel supporting 90 the frame and arranged for lateral turning movement and connected together in such a manner as to cause them to turn as a unit, a steering arm fixed to the foremost wheel spindle and a steering rod connected with the steering arm and normally extending 95 parallel to the steering strut, the draft member being secured to the steering arm.

2. A plow comprising a supporting frame, plowing devices carried by the frame, a 100 draw bar fixed to the frame at an acute angle to the direction of the movement of the plow, a steering strut fixed to the front end of the frame at right angles to the direction of the movement of the plow, a 105 flexible draft member adjustably connected to the draw bar and the steering strut whereby the point of drag of the plow may be altered, furrow wheels and a land wheel supporting the frame and arranged for lateral turning movement and connected together in such a manner as to cause them to turn as a unit, a steering arm fixed to the foremost wheel spindle and a steering rod connected with the steering arm and 110 extending parallel to the steering strut, the draft member being adjustably secured to the steering arm. 115

In testimony whereof I affix my signature.
JOHN W. MORGAN.
